ABSTRACT: A ski binding releasing the skier's boots from the ski on command of the skier by release of mechanical switches positioned in the grips of the skier's ski poles and connected to the ski bindings by cables in the skier's garments. A backup release system is actuated automatically when the tension or torsional forces between the bindings and the skier's boots exceed preset limits.

RELEASABLE SKI BINDINGS AND ACCESSORIES

BACKGROUND OF THE INVENTION

1. Field of the Invention

The present invention relates to bindings for skis, and more particularly, to devices for attaching skis to boots and for safely releasing them, automatically or on command, at the skier's option.

2. Description of the Prior Art

Until now various ski bindings have been devised which purport to provide safety by automatically releasing the boot from the ski binding when the tension or torsional forces between the two exceeds certain limits. The limits are determined by the setting given the binding. The likelihood of a timely release is high for loosely attached bindings and low for tightly set bindings. Thus, the degree of safety varies inversely with the tightness or binding force set in the binding. However, the effect on ski performance is reversed, since ski performance is enhanced by the degree of firmness and adherence of the boot to the ski. A very tight attachment will permit excellent control; a looser connection between the boot and ski will make control more difficult and might induce a fall. Existing bindings, therefore, at best offer a compromise between controllability of the skis and safety.

The present invention provides various embodiments of ski bindings and accessories the object of which, when used together or alone, is to solve problems in the following major areas:

1. Binding the boot firmly to the ski so as to provide positive control of the ski by the skier;
2. Providing complete release of the boot from the ski on COMMAND from the skier with two additional options, (a) a partial release on COMMAND and (b) a back-up AUTOMATIC release (the command feature provides further safety in that it actuates on reflex action in the event of an unanticipated fall);
3. Proving "step-in" convenience in attaching the ski to the boot; and
4. Providing forward release from the toe in the event of sudden resistance of the ski to forward motion.

SUMMARY

With these and other objects in mind, an apparatus in accordance with the invention includes toe and heel units for clamping the toe and heel respectively to the ski. Facilities are provided for biasing at least one of the toe and heel units longitudinally toward the other to grip the boot therebetween. A latch device holds the toe and heel units in their gripping position during normal operating conditions. Facilities are provided which are controlled by the skier during the act of skiing for releasing the latch device on command to move said toe and heel units longitudinally apart so that the boot may be extricated from the ski.

DRAWINGS

Other objects, advantages, and aspects of the invention will become apparent by reference to the following detailed description of the invention and drawings of specific embodiments thereof, wherein:

FIG. 1 shows a skier using the bindings and accessories in accordance with the invention;

FIG. 2 is a perspective view of a first embodiment of the invention applied to a cable type binding;

FIG. 3 is a detail perspective view of a catch for holding in position a release cable;

FIG. 4 is a cross-sectional view of a release element in the locked position;

FIG. 5 shows the release element of FIG. 4 in its released position;

FIG. 6 is a perspective view of a second embodiment of a ski binding in accordance with the invention on a cable type binding;

FIG. 7 is a cross-sectional view taken along line 7-7 of FIG. 6 with portions removed;

FIG. 8 is a cross-sectional taken along line 8-8 of FIG. 7;

FIG. 9 is a perspective view of a cable connector;

FIG. 10 is a cross-sectional view of the connector shown in FIG. 9;

5 FIG. 11 is a perspective view of a release switch which is mounted on the skier's body;

FIG. 12 is a perspective view of the release switch shown in FIG. 11 with the top broken away;

10 FIG. 13 is another embodiment of a release switch shown with the top removed;

FIGS. 14a-e are diagrammatic views showing the operation of the release switch of FIG. 12;

15 FIG. 15 is a side elevation view of a handle mounted command release mechanism shown partially in cross section;

FIG. 16 is the release mechanism shown in its partially released position;

17 FIG. 17 is the release mechanism shown in its total release position;

35 FIG. 25 is a detail cross-sectional elevational view showing the connection of segments of the cover plate;

FIG. 26 is a detailed cross-sectional elevational view of guide and roller members;

40 FIG. 27 is a detailed cross-sectional elevational view showing the rollers on which the transmission plate moves;

FIG. 28 is a perspective view looking forward showing the sole plate in the raised position;

45 FIG. 29 is a detailed perspective view looking rearward of the forward shock release mechanism;

FIG. 30 is a detailed perspective view of the release mechanism for the embodiment shown in FIG. 19;

FIG. 31 is a perspective view of a fourth embodiment of a ski binding in accordance with the invention;

50 FIG. 32 shows the ski binding of FIG. 31 in the released position;

FIG. 33 shows the ski binding of FIG. 31 just as it is being released;

55 FIG. 34 shows the ski binding of FIG. 31 in the locked position;

FIG. 35 is an in detail perspective view looking forward, with portions removed, showing the housing for the heel binding unit;

60 FIG. 36 is a perspective view with portions removed looking rearward and showing the heel retaining unit for the embodiment of FIG. 31;

FIGS. 37a-c show the release mechanism in various positions;

65 FIG. 38 is a perspective exploded view looking forward showing the hinged connection for the heel binding unit;

FIG. 39 is a detail perspective view of the command trigger release;

FIG. 40 is a detail perspective view of the latch;

70 FIG. 41 is a perspective view of a fifth embodiment of a ski binding in accordance with the invention;

FIG. 42 is a perspective view showing the binding of FIG. 41 during an upward release;

FIG. 43 is a detailed perspective view with portions removed of the heel unit of the embodiment shown in FIG. 41;

75 FIG. 44 is another perspective view of the heel unit;

FIG. 45 is a perspective view with portions removed of the release mechanism of the embodiment shown in FIG. 41 looking downward and forward;

FIG. 46 is a detailed perspective view looking from underneath the carriage block of the binding showing FIG. 41;

FIG. 47 is an exploded perspective view of the carriage block shown in FIG. 46;

FIG. 48 is an inverted perspective view of the retaining arm shown in FIG. 43;

FIG. 49 is a cross-sectional elevational view taken along line 49-49 of FIG. 43;

FIG. 50 is an exploded view showing the heel retaining bracket for the ski binding shown in FIG. 41;

FIG. 51 is a detailed perspective view with portions removed of a bracket shown in FIG. 45; and

FIG. 52 is an enlarged perspective view showing the various motions imparted to the mechanism to effect an automatic release.

DESCRIPTION OF THE INVENTION

In general, in order to accomplish the first purpose of firmly binding the boot to the ski, two units (toe and heel) attached to the ski lock onto the toe and heel of the boot as the boot is pressed onto the ski. This downward boot action also energizes the binding's release springs. Releasability of the boot is independent of binding force on the boot. In order to achieve a command release, the bindings are discharged by means of cables, resembling a bicycle brake cable, connected to controls located on the ski pole handles within the skier's grasp and actuated by his command. The third objective, step-in attachment of the binding, is obtained by means of the tightening effect of a hinged sole plate as it is depressed against the ski during the step-in action of the boot.

The objective of a forward shock release is accomplished by mounting the binding's toe unit on a base plate that translates forward when forward toe pressure exceeds a preset threshold.

A general descriptive view of the principal elements of this binding is given in FIG. 1. The binding itself may be released either by the AUTOMATIC mode or on COMMAND. Before starting, the skier can adjust the hand the strength required for automatic release, and also the extent (total or partial) of release. At maximum setting no automatic release is possible; at minimum setting the slightest force of the boot away from the ski will release the binding.

Without the command features, the binding may be used as an automatic releasable binding only. Used in this manner, it retains the advantage over conventional bindings of providing forward shock release and total or partial release (i.e. relaxation) as desired.

This invention also relates to a COMMAND/AUTOMATIC releasable binding of the cable type. This version represents a relatively inexpensive embodiment of the concept of COMMAND/AUTOMATIC releasable ski bindings. Like current cable releases this binding is not of the step-in type. Both embodiments use the same types of release cables, release switches and command release units.

In FIG. 2 there is shown one embodiment of the cable type of COMMAND/AUTOMATIC release binding in which the release is applied directly to a binding cable 21. The binding includes the elements common to standard cable-type bindings: (1) a forward lever 22 used to tighten and lock the binding which is adjustable to vary cable tension; (2) a toe unit 23 immediately forward of the boot and engaging the forward part of the boot sole upon tension of the binding cable 21 (this unit is held in place by a vertical shaft 24 about which it is free to rotate left or right); (3) two cable hooks, 26 and 27, permitting different settings of the binding. In the cable type of binding the portion of the cable 21, which extends around the heel of the boot, constitutes the heel unit. The toe unit 23 in this embodiment is stationary in the longitudinal direction; whereas the heel unit, i.e., the cable 21, is movable longitudinally to grip the boot between the heel and toe units.

The improved binding shown in FIG. 2 differs from the standard cable binding in that it can be released at the command of the skier. Cable 21 includes a latch or release element 31 which is connected to a release cable 32 extending upward along the wall of the boot and entering the skier's trousers. Release cable 32 is held in place against the boot by means of a bracket 33 attached to the edge of the boot sole. It can be readily inserted in the bracket 33 by depressing a tab 34, as shown in FIG. 3. A metal bulb attached to the wall of the release cable 32 limits movement of the cable 32 through the bracket 33 upon separation of the boot from the binding. Thus, the portion of release cable 32 extending from release element 31 to the bulb 36 acts as a retaining or "safety strap" on the ski in the event of binding release. A cable connector 100 links the lower part of release cable 32 to its extension into the ski trousers. The connector 100, which is described in detail hereinafter, can be disconnected easily when the boot is removed from the binding.

The operation of the cable release element 31 is shown in detail in FIGS. 4 and 5. The release element 31 includes a hard metal cylinder 41 which receives a smaller metal cylinder 42, terminating in a spherical cavity 43. The cylinders 41 and 42 are screwed together and held in a fixed position with respect to one another by an annular threaded ring 44. The base of the cylinder 41 has an aperture 46 to permit free passage of a cable core 48 of release cable 21. The cable core 48 extends into the cylinders 41 and 42 and terminates in a hard metal ball 51, which can be seated in the spherical cavity 43 or move longitudinally inside the cylinders 41 and 42. The external surface of ball 51 is firmly secured to the other end of the cable core 48. A coil spring 52 positioned inside cylinders 41 and 42 normally urges ball 51 into cavity 43. A hard metal plunger 53 holds the ball 51 in the spherical cavity 43 when the plunger occupies the position shown in FIG. 4. The cable 32 includes a cable core 54, and is fixedly attached to the cylinder 42 as shown at 56. When tension is exerted on the cable core 54 of the release cable 32, the plunger 53 recedes along a channel 57.

FIG. 4 shows the release element 31 when the binding is in the locked position. The binding cable core 48 is under tension, as indicated by the arrows on the left and the right, and plunger 53 is positioned so as to prevent the egress of ball 51 from spherical cavity 43. Upon command, as shown by arrow 58 in FIG. 5, the cable core 54 draws the plunger 53 along channel 57 thereby liberating the ball 51 to egress from chamber 43. Ball 51 then yields to the tension of the binding cable core 48 and moves to the base of cylinder 41. The ball 51 is cushioned by the compression of coil spring 52. As a result, the total length of the cable 48 binding the boot to the ski is increased by approximately the distance which existed between the ball 51 in its initial position (FIG. 4) and its final position (FIG. 5). The relative setting of cylinders 41 and 42 which controls the length of the cylindrical chamber through which ball 51 travels, therefore determines the amount by which the original binding force applied to the boot is reflexed. Depending upon the adjustment made, the boot is either totally released or sufficiently loosened to assure its separation from the ski in the event of a fall.

After the boot has left the binding, the binding cable core 48 is no longer under tension, and spring 52 is free to decompress causing ball 51 to return to its original position in the spherical cavity 43. When the hand controlled pole release units 200 (described hereinafter) are reset, release cable core 54 is forced in the direction of arrow 61 (FIG. 5), and plunger 53 returns along channel 57 to its original position (FIG. 4), once again locking the ball 51 in cavity 43. The release element 31 is now ready to be used again. The outer surfaces of cylinder 41 and of locking ring 44 may be corrugated to facilitate screwing of these parts into the desired positions.

In FIGS. 6-8 there is shown another embodiment of a cable-type COMMAND/AUTOMATIC ski binding. In this embodiment the latch release is applied to the lever 71 used to apply tension to the binding and lock it into position, instead of the binding cable. Lever 71 (similar to lever 22 in FIG. 2) is

mounted immediately forward of the boot. As it is depressed by forward rotation, around a hinge 72, tension is imparted to a binding cable 73 which loops around the upper part of the heel in the conventional manner forcing the boot against the surface of the ski and forcing the toe forward against a toe retaining unit 74. Under torsion the toe unit 73 can pivot right and left about a vertical holding pin 76 eventually disengaging the toe, as in conventional safety bindings. However, the toe unit 74 also slides lengthwise on a guide rail 77 along the ski centerline as seen in FIG. 8. Rotation of lever 71 extends forward and downward to a point where, unless held down, the lever would be constrained by the tension of binding cable 73 to return to a vertical position. However, lever 71 is held down by a latch 78 which engages a tip 79 of lever 71.

The latch 78 is supported for sliding movement in a release mechanism 81 which includes a hollow housing 82. Inside housing 82 is a support bracket 83 to which is attached the sheath of a release cable 84 (similar to cable 32, FIG. 2). The core 86 of cable 84 passes through an aperture (unnumbered) in bracket 83 and is attached to the forward end of latch 78. A compression spring 87 normally urges the latch rearwardly so as to be in a holding position for the lever 71.

Upon COMMAND release conveyed through the release cable 84 the latch 78 moves forward in the direction of the arrow, freeing lever 71. Thereupon lever 71 rotates upward and backward to relax the tension in cable 73. This rotation is aided by a leaf spring 88 which is compressed when lever 71 is latched in the forward position. The compression spring 87 resets the latch 78 after a release. It is to be understood that other latch mechanisms could be used. For example, the latch 78 could be pivoted laterally so as to release the lever 71.

Additional facilities are provided to insure that the toe unit 74 is separated from the boot on COMMAND. At the lower end of the lever 71 there is provided a gear segment 91 which is meshed with a rack 92. The rack 92 is secured to a shaft 93 extending forwardly from the toe unit 74. The shaft 93 is freely mounted inside a housing 94 on the forward end of the toe unit 74. A compression spring 95 mounted around the shaft 93 urges the rack 92 and the toe unit 74 apart. When lever 71 is locked in its down position, the spring 95 is compressed by the movement of the rack 92 and the gear segment 91, thus urging the toe retaining unit 74 against the skier's boot. When lever 71 is released by the latch 78, the rack 92 is moved forward to relieve the compression on the spring 95. This permits the retaining unit 74 to move forward on the guide rail 77 to disengage the boot from the retaining unit 74. The boot can now pivot more freely out of the toe unit, assuring a safe release in the event of a fall.

As shown in FIGS. 1 and 2, cable 32 extends upward inside the ski trousers through the cable connector 100. The connector 100, shown in detail in FIGS. 9 and 10, links the upper and lower parts of the release cable end to end so as to transmit without slack or distortion impulses applied to cable core 54. The connector 100 has a top 101 and a bottom 102 that form a rigid housing when snapped together. The bottom 102 is secured to the lower portion of cable 32; and the top 101 is secured to the upper portion of cable 32. The top 101 and bottom 102 are generally rectangular in shape and can be made of metal, plastic, or other material. The upper end of the top 101 and the lower end of the bottom 102 are faired in the shape of cones 106 and 107, respectively, in which the cable 32 is received. The top 101 and bottom 102 are snapped together. The two sidewalls 108 (one shown) of the top 101 terminate at the open end in small panels 109 turned inwardly. These fit against similar panels 111 (one shown) of the bottom where the top and bottom of the cable connector are joined, preventing longitudinal displacement of one part relative to the other. Vertical separation is prevented by a single row of knobs 113, on each side of the bottom 102 which engage in a longitudinal groove 114 of the top 101 when the top and bottom are joined. The knobs 113 and grooves 114 act as a snap mechanism. Disconnection of connector 100 is achieved by pulling on a metal tab 116 extending from the top 101.

The top 101 and bottom 102 contain mating elements 117 and 118 respectively, which are in the form of opposed square teeth which interlock to prevent relative longitudinal movement. The square teeth 117 and 118 mate with essentially no slack in the cable 32. The mating elements 117 and 118 can move lengthwise together either way about 1½ inches inside their respective top and bottom housings. However, they are prevented from moving up or down or sideways by the walls of the housing and by retaining brackets 122. As the top 101 and bottom 102 are pressed together the square teeth elements 117 and 118 come into contact with each other so as to effect a continuous connection between the upper and lower ends of cable 32 with no appreciable slack. It is to be understood that the mating elements 117 and 118 may take other forms so long as they permit little or no slack and can easily be snapped together.

In FIGS. 11-14 there are shown two embodiments of a release switch, designated generally 140, which gives the skier the option of COMMAND releasing the binding when either his right hand or left hand command release 200 is actuated (SINGLE), or only when both are actuated (JOINT). In either case, SINGLE or JOINT release, the bindings of both boots are simultaneously released.

The principle of operation is diagrammatically shown in FIGS. 14a-b where the release switch 140 is set for SINGLE release. Command release cables 141 and 142 from the left and right hands of the skier lead into switch 140 and are there connected with a single release cable 143 which splits into two strands 32 and 32' leading to the left and right ski bindings. The connection of cables 141 and 142 to cables 32 and 32' is through a pair of overlapping plates 146 and 147. Plate 146 is rigidly secured perpendicular to a base plate 148 which undergoes translation upon the pull of one or both of cables 141 and 142. Cables 141 and 142 are semirigid and are joined by means of a flexible cord 151 that loops around a pulley 152 extending upward from base plate 148.

The plate 147 is rigidly secured to a frame 153 that is free to slide on base plate 148. Release cable 143 is rigidly secured to an end wall 154 of frame 153.

Frame 153 may be positioned through lateral translation into one of two positions as shown in FIGS. 14a and 14c. In the SINGLE release position (FIG. 14a) the upstanding plate 146 partly overlies the plate 147 so that a pull from either release cable 141 or 142 results in a longitudinal displacement of plate 147 via the plate 146 and the base plate 148. This pulls the release cable 143 in the same direction thereby sending a release command to both of the ski bindings (FIG. 14b).

In the JOINT release position (FIG. 14c) frame 153 has been moved laterally (to the left) so that plates 146 and 147 are no longer in an overlapping position. If either cable 141 or 142 is pulled (but not both) as a result of a hand release, base plate 148 is moved longitudinally but this motion is not transmitted to frame 153. In such case, plate 146 would move to a position adjacent to the end wall 156 of frame 153 (FIG. 14d) but would exert little or no force thereagainst. This result is achieved, of course, by setting the amounts of motion which are imparted to the cables 141 and 142 by the hand release mechanism 200. On the other hand, if both cables 141 and 142 are pulled (FIG. 14e), plate 146 is moved twice as far thereby engaging the end wall 156 and imparting longitudinal movement to the frame 153 and its associated release cable 143.

In either of the SINGLE or JOINT release setting, the amount of movement imparted to the release cable 143 is approximately one-half of the movement imparted to cables 141 and 142. Therefore, the hand release mechanisms 200 must impart to their respective cables twice the pull distance required to release the binding itself.

As shown in FIG. 12, switch 140 is encased in a housing 161 with openings 162 and 163 at its ends for receiving release cables 141-142 and 32-32', respectively. The opening 162 is provided with two contiguous sleeves 164 to which are attached the sheaths of release cables 141 and 142 extending

from the hand release units 200. A single conical sleeve 165 extends from the opening 163 which is attached to the sheath of release cable 143. Release cable 143 leads to a Y-shaped conduit 166 in which the cable separates into two strands 32 and 32' leading to the left and right ski bindings.

As shown in FIG. 14b, base plate 148 is restrained from moving freely along the bottom of housing 161 by means of two relatively weak compression springs 167 (one shown), disclosed in the extended position. The springs 167 are guided by two straight metal rods 168 (one shown), which extend along the axes of springs 167. The ends of rods 168 are positioned in passageways 169 in base plate 148 for support and guidance. Whenever base plate 148 is moved as a result of a pull by either cable 141 or cable 142, springs 167 are compressed. The energy stored in the springs 167 is sufficient to later return the base plate 148 to its position shown in FIG. 12.

The top of housing 161 is covered with a panel 171 (FIG. 11) having an opening 172 therein. Adjacent to the opening 172 indicia may be placed designating position "1," for SINGLE release, and position "2," for JOINT release.

Positioned on the frame 153 is a switch actuator 176 which fits into opening 172. The actuator 176 is mounted on two parallel rails 177 (FIG. 12) secured to the top of frame 153. As shown in FIG. 11 the actuator 176 is in the SINGLE release position wherein wall 146 and wall 147 are in an overlapping position (FIG. 14a). Movement of the switch 176 to position "2", with the concomitant movement of frame 153, places walls 146 and 147 in a nonoverlapping position as shown in FIG. 14c.

When the binding is released, due to the actuation of release cables 141 and/or 142, frame 153 moves in the direction of arrow 178 (FIG. 12) while actuator 176, being constrained by the opening 172, remains stationary with respect to panel 171.

As an alternative to the design shown in FIGS. 12 and 14, release cables 141 and 142 can be connected to toothed racks 181 and 182 positioned inside housing 161. The racks face inwardly and have positioned therebetween a pinion gear 183. The pinion is secured by an arm 184 to end wall 156 to convey the motion of the racks to the plate 146 and thereby to housing 153 and the cable 143. The switching arrangement from SINGLE to JOINT is the same as that shown in FIG. 11. If the actuator 176 is on JOINT the movement imparted to pinion 183 by either cable 141 or cable 142 alone is insufficient to actuate the release of the bindings. However, if both of the racks 181 and 182 are moved in response to their respective cables 141 and 142 the pinion 183 is given sufficient movement to move frame 153 thereby actuating the release cable 143.

As shown in FIGS. 15-17 a hand held command release mechanism 200 is secured to the end of each of the skier's poles 201. A movable handle grip 202 is connected to the pole 201 by a lower bifurcated arm 203 and an upper bifurcated arm 204. The furcations of arm 203 are connected through the body of pole 201 on a pivot pin 205 positioned in slots 206 (one shown). The furcations of arm 204 are connected to the body of pole 201 by a pin 207 which is free to move longitudinally in slots 208 (one shown). Arm 203 includes at its outer end a crossbar 211 having generally rectangularly shaped knobs 212 which extend beyond the surface of grip 202. When handle grip 202 is in the depressed position shown in FIG. 15 crossbar 211 fits into a cutout portion 213. Knobs 212 are positioned in the circular portions 214 of cutout 213 and are held there so long as knobs 212 are positioned obliquely relative to the exit slit 216 (FIG. 15). As the upper end of handle grip 202 is allowed to rotate outward (FIG. 16), the position of knobs 212 inside cutout 213 changes until crossbar 211 reaches a position where it is freed from the body of the ski pole 201.

Handle grip 202 is normally urged away from the body of the ski pole 201 by a compression spring 221 housed inside a pair of telescopic cylinders 222 and 223. The base of cylinder 222 is secured to the inner side of pole 201; whereas cylinder 223 is free to move longitudinally with its outward tip 224

being rounded and in engagement with the underside of handle grip 202 between walls 225. Attached at the midpoint of crossbar 211 is the end of one of the release cables 141 or 142 (FIG. 17). Therefore, movement of crossbar 211 outwardly away from ski pole 201 causes a pull to be supplied to the connector switch 100, previously described in FIG. 10.

Spring 221 causes rotational movement of handle grip 202 about crossbar 211, but its position at the lower portion of handle grip 202 minimizes the torque required at the top of the handle to restrain rotation. Therefore, a normal grip by the skier's hand is all that is required to prevent release. However, if handle grip 202 is permitted to rotate fully around crossbar 211, as shown in FIG. 16, the binding does not release so long as the bottom portion of handle grip 202 is not permitted to separate from the body of ski pole 201. Thus, only when the skier's hand is fully opened does the handle grip complete its movement at both ends thereby causing the binding to be released (FIG. 17).

20 In order to reset hand release mechanism 200, the bottom portion of handle grip 202 is first depressed manually until it is in contact with the stock of ski pole 201. Next, holding the bottom part in position, the upper portion of handle grip 202 is depressed until it comes in contact with the stock. As this 25 occurs, arm 203 is depressed and crossbar 211 is brought back into cutout 213. As arm 204 is depressed pin 207 moves downward in slots 208. Thus, as shown in FIG. 15, knobs 212 on crossbar 211 are locked into the circular portion 214 of cutout 213 preventing release thereof. A safety switch 226 is 30 provided on the uppermost end of ski pole 201 for retaining handle grip 202 in its closed position. The curved tip 227 of switch 226 is merely moved into an overlapping relationship with the upper edge 228 of handle 202 to preclude inadvertent release.

35 In FIGS. 18-30 there is shown one embodiment of a step-in COMMAND-AUTOMATIC releasable ski binding, designated generally 300. In order to lock the boot to the ski, the skier introduces his boot toe against a binding toe unit 301 and then presses his boot sole against a sole plate 302. A binding heel unit 303 includes a heel plate 304 which is hinged at 305 to sole plate 302. Heel unit 303 and heel plate 304 rotate forward until plates 302 and 304 are coplanar against the surface of the ski. As this occurs, heel unit 303 engages the heel 40 of the boot thereby locking the boot by its sole between toe unit 301 and heel unit 303 (FIG. 19).

45 As shown in FIG. 19, toe unit 301 rests on a cover plate 306 which extends rearward under sole plate 302 and under heel unit 303. Cover plate 306 encloses most of the elements of the 50 binding mechanism to shield them from the snow. Also, toe unit 301 is protected by a fairing 307 (FIG. 18), and heel unit 303 is protected by a fairing 308.

55 As binding 300 is released, either on COMMAND or by AUTOMATIC, two actions take place: (1) toe unit 301 is propelled forward in the direction of arrow 311 (FIG. 18), releasing the toe of the boot either totally or partially depending upon the setting of the binding; and (2) heel unit 303, together with heel plate 304 are released and free to rotate upward as indicated by arrow 312.

60 In the COMMAND release mode, the boot is released when the skier actuates the release cables 32 by means of hand release mechanisms 200. In the AUTOMATIC release mode, the boot is released (1) if sufficient rotational force relative to the ski is exerted laterally at either the toe unit 301 or the heel unit 303, or (2) if sufficient upward force is exerted on heel unit 301, or (3) if a sudden resistance to forward motion is encountered by the ski, thereby releasing toe unit 301.

65 In FIG. 19, the binding is shown with the toe and heel unit 70 protective fairings 307 and 308 removed. Heel unit 303 and toe unit 301 are identical except for base side plates 316 which extend on either side of the forward part of heel unit 303. Units 303 and 301 are hinged at the tapered end to tabs 317 and 318, respectively, that are screwed to the body of the binding. 75

Two adjustment screws 319 pass freely through holes drilled through base side plates 316 of heel unit 303, and are screwed to heel plate 304. On each side, a spring 321 is inserted between the head of screw 319 and the upper surface of base side plates 316. This allows heel unit 303 to rotate upward and backward about a hinge 322 when sufficient upward force is applied on the heel unit 303 to offset the restraining force exerted on base side plates 316 by springs 321. By contrast, toe unit 301 is not allowed to rotate about a comparable hinge 323, but is held firmly against the base of the binding by a pair of screws mounted inside of the unit.

As shown in FIG. 19, a pair of locking brackets 326 extend outward on both sides of the heel plate 304. Brackets 326 lock by means of hinged side panels 327 onto vertical retaining plates 328 protruding from cover plate 306 on each side of the ski. When the binding is released, retaining plates 328 surge forward along side openings 329 of cover plate 306, freeing locking plates 326 to move upward. This allows heel plate 304 and heel unit 303 to rotate upward and backward.

Locking brackets 326 are held inside channels 331 on each side of heel plate 304 by means of saw-toothed edges 332 and two pairs of vertical screws 333. This arrangement permits the binding unit to be used on skis of different widths. Likewise, retaining plates 328 may be adjusted to various ski widths as shown in FIG. 21.

Hinges 334 of locking brackets 326 are spring loaded so that when side panels 327 are forced outwardly, as shown at 327', they are constrained to return to their vertical position. Thus, when the binding frame is in the open position (FIG. 20), the planes of side panels 327 are parallel to retaining plates 328. As the binding is closed by pressure of the skier's boot on sole plate 302, a bottom lip 336 of panel 327 will strike the upper ridge of retaining plate 328 causing the panels to cam outward until the bottom of lip 336 has cleared the bottom of plate 328. Thereafter, locking plates 328 snap back into a vertical position to lock against plates 328.

Two arresting blocks 337 (FIG. 20) are located on the underside of heel plate 304 against the forward hinge 305 and along the side edges of plate 304. These blocks 337 limit the downward movement of heel plate 304 to a level where the plate in its fully depressed position is parallel to the ski's upper surface. Blocks 337 are dimensioned according to the space provided under heel plate 304 as a result of the camber of the plate designated 338, just forward of a rear hinge 339. The space is provided to accommodate a command release mechanism 341.

Sole plate 302 is hinged at its forward end through six extensions 344 that fit into longitudinal grooves 346 provided on cover plate 306. At the forward end of the binding there is a plate 347 on which toe unit 301 is mounted by means of four screw holes 348. As shown in FIG. 21, the ski binding rests on a base plate 349 extending the entire length of the binding.

An important element of the ski binding is a transmission plate 352, that extends from a rear arresting block 353 to a forward arresting block 354. Arresting blocks 353 and 354 limit the travel of transmission plate 352 along the length of the binding.

Transmission plate 352 is sandwiched between base plate 349 and cover plate 306. It contacts plates 349 and 306 through a series of rollers 356. In the forward part of the binding, the rollers are of larger diameter to provide for the greater vertical separation needed there between base plate 349 and cover plate 306. This greater separation is required to insure that the top surface of sole plate 302 is flush with the forward part of cover plate 306 when the binding is in the locked position shown in FIG. 19.

Rollers 356 are comprised of pairs of pins 357 and 357' stacked vertically, as shown in FIG. 27. Pins 357 and 357' are mounted in a well 358 provided in transmission plate 352, and held in position by two sets of grooves 359 (FIG. 21) into which fit the axles of the pins.

Transmission plate 352 is segmented in three parts by means of forward hinges 361 and rear hinges 362. This allows

the binding to conform to vertical deformations of the ski along its length as the skier proceeds over depressions and moguls. During release, transmission plate 352 moves forward then backward inside the binding between retaining blocks 353 and 354. The shock of contact is absorbed at the forward end by a pair of spring blades 363 attached to the front end of transmission plate 352. Plate 352 can be reinforced as shown at 364 (FIG. 21). Forward block 354 may be set at different positions on the longitudinal axis of the binding by means of an adjustment knob 365 which screws retaining block 354 to any of several points on a guide plate 367 rigidly attached to base plate 349.

When the binding is in the locked position shown in FIG. 19, transmission plate 352 is in its rearmost position resting against retaining block 353 (FIG. 21). When the binding is released, transmission plate 352 is propelled forward (by means described hereinafter) until it reaches forward retaining block 354. As this occurs toe unit 301 moves forward freeing the boot's toe partially or totally, depending on the adjustment selected, and heel unit 303 is freed to rotate upward and rearward. The extent of release is determined by the distance of forward travel of transmission plate 352, and hence by the position of retaining block 354 selected through knob 365.

In FIGS. 21 and 29 there is also shown a forward shock release unit, designated generally 367. The function of this adjustable unit 367 is to release the skier's toe unit in a forward direction upon sudden frontal impact of the ski against an obstacle or when resistance of the ski to forward motion is abruptly increased.

Toe base plate 347 on which is mounted toe unit 301, is screwed to a plate 368 which is cradled in a frame 369, attached to transmission plate 352. The assembly is such that plates 347 and 368 can only move in the forward direction relative to frame 369. They are prevented from rearward movement by a retaining bar 371. Plates 347 and 368 can move forward only if the ski, and hence frame 369, are subjected to a sudden shock sufficient to overcome the resistance of two side latches 372 (one shown) extending laterally from plate 368 to impinge on the rear edge of frame 369. If this level of shock occurs, the movement of plates 347 and 368 relative to frame 369 will continue until arrested by protrusions 373, which are mounted on plates 347 and 368, come into contact with the rear edge of frame 369. The position of frame 369 with respect to frame 352 can be adjusted by a pair of knurled pins 370 which fit in holes 370a.

The resistance of latches 372 (FIGS. 21 and 29) to retraction inside plate 368 when subjected to forward pressure, is controlled by a knob 373. Knob 373 is located immediately behind toe unit 301 and does not interfere with the movement of the ski boot into or out of the unit.

Latches 372 protrude from the slanted edges of plate 368, and are part of an assembly 374 shown in FIG. 29. Assembly 374 lies in a rectangular well 376 the long sides of which have upper ledges 377 which support two metal plates 378 (one shown), one attached to each of the latches 372. During forward shock release latches 372 recede into plate 368 along guide cavities 379. Plates 378 also assure rectilinear motion of latches 372. One latch is connected by a rigid shaft 381 to an exteriorly threaded hollow shaft 382. Shaft 382 is rigidly attached to the opposite latch (not shown). Free movement of shaft 381 inside shaft 382 is constrained by a helical compression spring 383. Spring 383 is held in compression between plate 378 and a geared wheel 384 that screws onto the outer surface of shaft 382. By turning wheel 384 its position along shaft 382 is changed to further compress or relax spring 383. In this manner the threshold of shock force required to retract latches 372 into frame 368 may be varied. Adjustment is made by the geared knob 373 which is in mesh with wheel 384. Knob 373 is wide enough to accommodate different positions of gear wheel 384 relative to it.

As shown in FIG. 21, transmission plate 352 is connected to the forward part of sole plate 302 by two spaced, longitudinal helical tension springs 394 (one shown) of elliptical cross sec-

tion. The rear ends of springs 394 are attached to lateral extensions 396 (one shown) of transmission plate 352; and the forward end is attached to sole plate 302 by means of brackets 397 shown in FIG. 28. Brackets 397 are attached to the extensions 344 of sole plate 302. Roller drums 398 mounted laterally between extensions 344 of sole plate 302 to translate smoothly on the surface of base plate 349. The middle section of cover plate 306, designated 306', is shown in detail in FIG. 28. When the skier locks on his skis (as shown in FIG. 18) the effect of boot pressure on sole plate 302 is to translate the plate's leading edge 399 forwardly until the plate is depressed to a horizontal position. As this occurs, transmission plate 352 is prevented from moving forward by a locking element 401 (FIG. 21) which blocks the path of its rear extremity. The rear end of springs 394 remain fixed to extensions 396, and forward motion of the front end of springs 394 puts these springs under tension. When the binding is released either on COMMAND or by AUTOMATIC, locking element 401 is released, allowing transmission plate 352 to be propelled forward under the tension of springs 394 acting on transmission plate 352 through their point of attachment at 396. The forward motion of transmission plates 352 continues until arrested by retaining block 354. The binding has now been released or relaxed, depending on the setting. A third spring 402 positioned between springs 394 is attached at its forward end to sole plate 302 in the same manner as springs 394. Its rear end, however, is attached to a support 403 which is independent of the transmission plate and is screwed firmly to base plate 349. As the boot is locked to the binding, spring 402 is also extended. However, when transmission plate 352 is allowed to move forward as the binding is released, spring 402 remains under tension as long as sole plate 302 stays depressed against the surface of the ski. When the skier's boot is removed from the sole plate, spring 402 will contract back to its normal position, causing sole plate 302 to resume its neutral oblique position, and also returning transmission plate 352 together with relaxed springs 394, back to their neutral position with the rear end of transmission plate 352 resting against retaining block 353. The binding is then in a neutral position and ready for reuse.

The release mechanism shown in FIGS. 20 and 21 will now be discussed in detail. As discussed previously, locking element 401 controls the movement of transmission plate 352. A release element 404 is attached to a release rod 406, whose directionality is assured by a sleeve bearing 407 through which the rod is connected with release cable 32. As shown in FIGS. 20 and 21, part of release mechanism 341 lies above cover plate 306, and part below. Release mechanism 341 is attached to the base of the binding by means of the vertical pin 411 which screws into a supporting element 412. Extending radially from pin 411 with a slight offset is a horizontal arm 413 (FIG. 30) that is hinged laterally at 414 to allow upward rotation of its far segment 416. Segment 416 terminates in a raised tab 417 which lies parallel to cover plate 306. Attached to arm 413 is a crescent-shaped plate 418, which serves as a snow cover for a window 419 in cover plate 306. Window 419 allows free movement both in the horizontal and vertical plane of locking element 401 secured to the underside of plate 418 by screws 421.

The actuation of mechanism 341 can be effected by a vertical pull on tab 417 causing rotation of arm 413 about hinge 414. This is the AUTOMATIC release mode. The release occurs when a hook 422 (FIG. 22) extending downward from heel release unit 303 and which latches underneath tab 417, is drawn upward. This occurs when heel unit 303 rotates upward and backward beyond a preset threshold about hinge 322 (FIG. 19) when sufficient upward pressure is applied by the skier's heel to exceed that threshold.

In FIG. 30, a portion of the release mechanism's snow cover plate 418 and cover plate 306 have been cut away to reveal the part of the mechanism located below the cover plate. Also visible is a portion of transmission plate 352 as it is held in place by locking element 401. Since the entire release

mechanism is hinged about vertical pin 411, as release rod 406 is withdrawn into sleeve bearing 407 and release element 404 comes into contact with locking element 401, the release mechanism pivots to the right about pin 411. Locking element 401 describes an arc of a circle centered about 411, while release element 404 moves rectilinearly. In the COMMAND mode, as the pull on release cable 32 proceeds release element 404 and locking element 401 eventually separate allowing the release mechanism to return to its neutral position by a restoring spring (not shown) on pin 411. Prior to separation, however, locking element 401 releases the rearmost end of transmission plate 352 which then surges forward and releases the binding.

When command release handles 202 are reset against the skier's poles, each release cable moves in its sheath outward from the pole to the binding, forcing release rod 406 to egress from its sleeve bearing 407. During this movement, release element 404 slides against the outer surface 426 of locking element 401. However, release element 404 is hinged to release rod 406 and spring loaded to return in the position shown in FIG. 44c. Therefore, as release rod 406 snaps back, release mechanism 341 is cocked ready for another release cycle.

Referring to FIG. 21, cover plate 306 is held in place by a number of vertical spacing pins 427. Pins 427 are of two sizes; the smaller size being used in the rear part of the binding, the taller ones forward to accommodate the higher level of cover plate 306 there. Some of these pins 427 additionally serve to guide transmission plate 352 in its forward and rearward motion in the binding. For this purpose, the central portion of pins 427 consists of a spin drum 428 (FIG. 26). Drums 428 can spin freely about a central core 429 forming the shaft of pin 427. Shaft 429 is screwed at its lower end into the ski through base plate 349. Shaft 429 is hollow and threaded on the inside to accommodate a screw 431 by means of which cover plate 306 is secured to pin 427. Spinning of drum 428 about shaft 429 is facilitated by a disc 432 inserted between base plate 349 and drum 428 and a flange 433 on the upper part of shaft 429. The flange also serves as support for cover plate 306 which is sandwiched between it and the lip of screw 431. Any upward force exerted by the boot on the ski binding will be transmitted by toe unit 301 and heel unit 303 to toe plate 347 and heel plate 304, respectively. Except for the component of this force which is then transmitted through hinge 339 to tab 436, the remaining force is divided between the toe and heel parts of transmission plate 352. As transmission plate 352 is sandwiched between base plate 349 and cover plate 306, the upward force component will be applied principally to cover plate 306 in the vicinity of the toe and at the heel units. The number and distribution of vertical spacing pins 427 and supporting pins 356 are selected to meet this requirement. The thickness of cover plate 306 provides additional support.

The flexibility of transmission plate 352 along the longitudinal vertical plane of the ski is assured by the two sets of hinges 361 and 362 (FIG. 21). Two sets of lateral cuts, shown as 437, are provided in base plate 349. Lateral cuts are also provided in cover plate 306, as shown at 438 (FIG. 19). At the cuts, plates 349 and 306 terminate in matching vertical S-shaped cross sections. In FIG. 25 the plates are depicted in their neutral position where the two S's are in contact, but offset by about one-third of their length.

Toe binding unit 301 and heel binding unit 303 will now be described with reference being made to FIGS. 19 and 23. Heel unit 303 will be described in detail it being understood that the toe unit 301 differs only in minor respects.

Heel binding units 303 include a hollow frame 441, into which fits a core 442 and a binding bracket 443. The connection to the ski is by means of screws 319 and a pair of screws (unnumbered) through tab 317. However, when the unit is used as a toe unit, it is rigidly attached to toe base 347 (FIG. 21) by screws (not shown) passing through holes 446 on the inside base of frame 441 which are aligned with screw holes 348 on the toe base 347.

Core 442 fits directly into frame 441 and is secured there by means of a long screw 448 extending along a central tunnel 449 provided in core 442. Screw 448 is threaded at its bottom 451 to engage threads in an aperture 452 at the bottom of frame 441. A spring 453 permits limited vertical movement of core 442 within frame 441. A collar 454 around screw 448 helps to hold core 442 and frame 441 together.

Core 442 has an upper cap 455 provided with a cam 456 extending downward (FIG. 24). Cap 455 conforms with the contour of a well 457 in frame 441 with a cam surface 458. When core 442 is positioned inside frame 441, core 442 may be pivoted right and left about screw 448 which acts as an axis of rotation. In order to pivot, however, cam 456 must overcome the rising slope of cam surface 458 on which it rests. This requires core 442 to rise vertically along screw 448 against the restraining force exerted on core 442 by spring 453. Sufficient torque must be applied to overcome this resistance if release is to be effected. Once cam 456 passes a certain threshold of turn, however, cam 456 reaches the level part of cam surface 458, and further pivoting can occur without resistance. By setting screw 448, one may adjust the level of compression of spring 453, and, therefore, control the initial torque required to pivot core 442 right or left about its vertical axis. As core 442 rotates so does binding bracket 443 until the boot and the binding separate.

In order to assemble the entire release unit 303 bottom plate 461 of core 442 is removed. Core 442 is then introduced into an opening 462 in binding bracket 443, and bottom plate 461 is screwed back into place. Opening 462 of the binding bracket 443 is shaped geometrically similar to the outer cross section of core 442, only slightly larger. Also, binding bracket 443 has a thickness or height which is slightly less than the vertical distance separating the tiers or floorlike layers 463 of the core. In its normal position, shown in FIG. 22, binding bracket 443 is positioned at the desired level (depending on ski boot sole thickness) between the floors 463 of the core and held there by a spring loaded plunger 464 and by the overlap with core layers 463 between which it is inserted. As the binding locks onto the boot, pressure in the direction of arrow 466 increases the area of overlap. A spring loaded plunger 467 opposes rearward motion of the binding bracket 443 and provides longitudinal flexibility of the binding relative to the boot to accommodate flexing of the ski in the longitudinal vertical plane. By adjustment of screws 470 and 470' the initial position of binding bracket 443 may be modified as well as the distance of its displacement when the binding is locked on the boot.

The automatically releasable latch 422 (FIG. 23) which is installed only on the heel release unit 303, fits into two small grooves 468 in frame 441 and is held there by means of a screw 469 inserted through a larger groove 471. Overlaid on the face of latch 422 is a flexible steel blade 472 that is secured to the bottom plate of the frame 441 by means of two screws directly above the two small grooves 468. Mounted in this manner, latch 422 normally rests in a vertical position, but may be moved by rotation forward and upward against the force exerted by spring 472. After binding release, spring blade 472 forces latch 422 to rotate back to the vertical position. A shoulder 473 on the upper portion of latch 422 precludes any further rearward rotation.

When the binding is locked, as shown in FIG. 19, tab 417 of release mechanism 341 is engaged between the shoulder 473 and the bottom of latch 422. When an upward force is exerted by the skier's boot on heel release unit 303 with sufficient magnitude to compress base plate side springs 321, latch 422 is raised. If the movement is of sufficient magnitude, latch 422 will raise tab 417 causing the entire forward part of release mechanism 341 to assume a raised position. As this occurs, locking element 401 disengages transmission plate 352 and the binding is automatically released.

The space between shoulder 473 and the bottom of latch 422 is provided so as to absorb, without binding release, small upward rotations of heel release unit 303 caused by minor vertical shocks as the skier proceeds over the terrain. The degree

of shock that can be absorbed in this manner without producing a release is controlled by adjustment of screws 319.

It is to be understood that the toe unit 301 including the forward shock release mechanism is not necessary for the operation of binding 300. For example, a fixed toe unit could be used, and release could be effected wholly with the heel unit 303 in either the AUTOMATIC or COMMAND modes.

Another embodiment of a step-in COMMAND/AUTOMATIC releasable ski binding is depicted in FIG. 31, 10 designated generally 500. Binding 500 differs primarily from binding 300 in that the command release operates only on the heel binding unit. Instead of having the toe unit move forward and the heel unit released to rotate upward and rearward, on COMMAND toe unit 501 remains fixed and heel unit 502 moves backward from the locked-on position shown in FIG. 34 to the position shown in FIG. 33, and is then free to rotate upward and forward, as shown in FIGS. 31 and 32. The toe and release units 501 and 502 are substantially the same as units 301 and 303 shown in FIG. 19. Fairings such as those shown in FIG. 18 as elements 307 and 308 may also be added. In this embodiment vertical adjustment screws 503 are also provided on toe unit 501 to facilitate rotation in the event of a forward overhead fall.

25 Toe unit 501 is mounted on a cover plate 506 which is attached to a forward shock release unit similar to the one previously described in FIGS. 21 and 29. The only difference is that in this embodiment toe unit 501 and cover plate 506 are mounted directly on a forward shock release plate 507 as shown in FIG. 31. As before, plate 507 has a trapezoidal cross section that matches the cradle's section. Plate 507 is thus constrained to remain in contact with the upper surface of the ski. The forward shock release threshold strength is set directly with knob 511 reached through a window 512 in cover plate 506.

Serving as cradle for the forward shock release unit is a forward plate 513. Plate 513 is rigidly attached to the ski by a series of screws 514 along its periphery. Its rear edge is curved to form a hinge 516 about which the rear part of the binding is 40 articulated. The underside of plate 513 (FIG. 38) is provided with a groove 517 extending in a loop from the edge 516. Fitting into groove 517 is a complementary loop of a steel spring 518 that coils into a tubular frame 519 of the rear part of the ski binding. Frame 519 is U-shaped, the bottom of which hinges along the edge 516 of plate 513. The extremities of spring 518 extend straight for some distance along the legs of tubular frame 519. The purpose of spring 518 is to exert an upward torque on frame 519 to restore the ski binding to the position of FIG. 32, when not otherwise constrained. Insertion of spring 518 into frame 519 is accomplished by separating the frame by loosening a screw 521. Screw 521 fits into a groove 522 when frame 519 is joined in a unitary structure.

In FIGS. 31 and 38 there is also shown release cable 32 55 which enters the binding through frame 519 at 523, leaves the frame at 524, and connects with a release unit 526, described more fully hereinafter.

As shown in FIG. 31, frame 519 extends rearward to a pair of tubular segments 531 by means of which it is screwed to a frame 532, which is also U-shaped. Mounted on frame 532 is the heel assembly 535, shown in detail in FIGS. 35 and 36. Heel assembly 535 includes a base 536 to which is attached heel release unit 502, a pair of release springs 537 (one shown) enclosed in telescoping cylindrical shields 538, and two release blocks 539.

When the skier's boot is pressed into the binding (starting with the position shown in FIGS. 31 and 32) frame 519 is depressed against the ski, pivoting about hinge 516. Heel assembly 535 pivots on transmission arms 541 which are hinged on a rod 542 passing through a slot 543 in release unit 526. Heel assembly 535 slides along frame 532 guided by tunnels 544 in base 536. As this occurs, the release springs 537 are extended and restoring spring 518 is energized. Also, release blocks 539 free a latch 546 which is spring loaded about a hinge 547 to lock onto a projecting lip 548 of release unit 526.

At the same time an autorelease trigger 549 (FIG. 36) engages a tab 551 of the trigger transmission system, designated generally 552. The ski binding is now locked as shown in FIG. 34.

The details of release mechanism 526 are shown in FIGS. 37a-c. When released on COMMAND, the command impulse (pull) is transmitted by release cable 32 to a release rod release 558. The retraction of trigger release 558 (FIG. 37b) frees a latch 559 to pivot about a pin 561. As can be seen, the trigger release 558 overlies the forward end of latch 559 preventing the latch from rotating when the elements are positioned as shown in FIG. 37a. Latch 559 yields to the pressure exerted by rod 542 allowing the rod to surge backward along slot 543 under the effect of release springs 537 acting through heel assembly base 536 and transmission arms 541. Transmission arms 541 are hinged at their upper end by pins 562 (FIG. 35) to base 536 at 563 and at the other end to release unit 526 by means of rod 542 extending laterally through slot 543. The ski binding after release is shown in FIG. 33. The extend of release (total or relaxation) depends on the distance through which heel assembly 535 is withdrawn from the position of FIG. 34 to that of FIG. 33. This distance and hence the type of release desired can be preset by adjusting the position of nut 566 on frame 536.

In the mode shown release blocks 539 are designed to extend far enough to the rear to dislodge latch 546 from lip 548 by impact with the flat facets 567 (FIG. 40) of latch 546 regardless of the adjustment chosen for nuts 566. This insures the vertical release of the heel assembly 535. It is to be understood that release blocks 539 can be replaced by longitudinal screws which can be deployed to various lengths out of frame 536 in relation to the position of nuts 566. Thus, the vertical release of heel binding unit 535 may also be partial rather than complete.

In the AUTOMATIC release mode, (FIGS. 36, 37a-c) the upward pull of autorelease trigger 549 acts on tab 551 which pivots about a pin 571. This cams trigger release 558 forward and rod 542 is released as before. As shown in FIG. 39, the link between release rod 556 and command release trigger 558 is such that trigger 558 can be moved in the direction of arrow 572 without inducing any movement in the release rod. This is necessary since in this mode of release there is no COMMAND release and release rod 556 cannot be pushed forward. The return of trigger 558 to its neutral position (FIG. 37a) is assured by a relatively weak spring 573 interposed between trigger 558 and the forward wall of release unit 526.

Since the trigger action in AUTOMATIC release may be of extremely short duration, trigger 558 may have resumed its neutral position before latch 559 has returned to the position shown in FIG. 37a. In this eventuality, the return of the release mechanism to its normal position is assured because the contiguous edges of trigger 558 and latch 559 are cut obliquely to produce a catch action.

As in the COMMAND mode, AUTOMATIC release may be set for total or partial relaxation.

It is to be understood that AUTOMATIC release toe units 301, 303, 501 and 502 can be eliminated in the various embodiments, substituting in their place rigidly attached heel and toe units (not shown). In such case release would be dependent on COMMAND or on the forward shock release. It should also be apparent that the forward shock release or the COMMAND mode of release can be eliminated relying on the other forms of release. Also, the COMMAND mode or the AUTOMATIC mode alone is sufficient, although the degree of protection from an injurious fall is somewhat reduced.

Another embodiment of the safety release binding, designated generally 600, is shown in FIGS. 41-52. In this version, however, the entire COMMAND/AUTOMATIC mechanism is contained in the heel unit 601. The toe unit 602, as shown, is merely a fixed holding tab under which the ridge of the boot sole is inserted prior to the downward stepin motion of the heel against the ski to achieve lock. FIG. 41 reveals

the heel unit's three principal components (a) a base plate 606, serving as a cradle in which the assembly of the other two components travels; (b) a carriage block 607; and (c) a retaining arm 608 whose forward part holds a heel retaining bracket

5 assembly in two parts, 609 and 611 (FIG. 50). The position in phantom lines in FIG. 41 shows one form of release (sideways or twist), and FIG. 42 shows the other principal release position of the binding (upward). In both forms of release carriage block 607 is in the process of withdrawing rearward 10 on pins 612 and 612' along rails 613 provided in base plate 606. In both cases retaining arm 608 has remained rigid. FIGS. 43 and 44 show the condition of the arm 608 when the skier's boot is placed against the binding in the prelock position, when the forward part of retaining arm 608 is 15 extended and hinged upward. The hinge is a floating hinge centered about a horizontal pin 614 which can move parallel to the position shown, inside a pair of longitudinal slots 616 on both sides of the rear part of retaining arm 608. The prelock position of retaining arm 608 as shown in FIGS. 20 43 and 44, results from the joint action of a pair of tension springs 617 (FIG. 49) (one shown) housed inside the rear part 618 of retaining arm 608, and of a pair of spring blades 619 sandwiched between the rear and forward section of retaining arm 608 designated 618 and 621, respectively. 25 The spring blades 619 act with the tension springs 617 As the heel of the skier's boot presses down on heel racket 611 arm 608 is depressed downward and rearward extending springs 617 and compressing blades 619 until forward part 30 621 comes to rest against the forward extension of rear part 618 of arm 608. A latch consisting of a male member 622 and a female member 623 (FIG. 44) is closed and locks the arm 608 in the position shown in FIG. 41. The female member 623 of the latch consists of two tabs which, under pressure from the male member 622, retract laterally into two wells provided 35 in the forward extension of section 618. This retraction is effected against the action of springs (not shown) contained in the wells whose effect is to restore tabs 623 to their original position upon relief of pressure from male member 622. Thus, 40 when the downward motion of male member 622 is completed, tabs 623 lock forward section 621 in the horizontal position.

The heel retaining bracket assembly (FIG. 50) which is attached to a face 626 of arm 608 (FIG. 44) consists of two plates 609 and 611 with horizontally matching corrugated surfaces which also match the corrugated surface of face 626. Two pairs of vertical slits 627 and 628 on these plates and four screws (not shown) permit the plates to be fastened at the appropriate height and heel thickness level to the retaining arm 50 608.

The underside of the rear section 618 (FIG. 48) is provided with a vertical fin 631 of oval cross section, whose bottom face 632 slopes slightly upwards in the forward direction. When the binding is locked, the forward side of fin 631 presses against a retaining block 636 (FIG. 45) of the binding's trigger mechanism to be discussed below. Displacement of the skier's boot vertically or laterally relative to the ski causes fin 631 to migrate on the inner surface of the retaining block 636. When this migration exceeds preset limits the binding is released automatically. Alternatively, when the retaining block 636 is retracted on COMMAND, these limits are instantly reached and the binding is also released.

Once the boot is locked into the binding the two principal directions in which the binding can move are upward as in FIG. 42 and laterally as shown in phantom lines in FIG. 41. The upward motion the pull on the heel of the boot is transmitted by arm 608 directly to carriage block 607. In FIGS. 46 and 47 carriage block 607 is seen to consist of an upper part 637 and a lower part 638, which are hinged together by means of the pin 612 and held one against the other by a spring pin assembly 641. The force required to urge parts 637 and 638 open can be controlled by adjustment of a regulating screw 642. The bottom part 643 of assembly 641, into which screw

642 is threaded is inserted through a hole 644 drilled on the underside of part 638. A sleeve 646 provides the hinge about which retaining arm 608 pivots through a hole 647 in part 618. A spring 648 under compression by the action of screw 642 opposes the upward motion of part 637 relative to part 638. It is noted that the lower part 638 is precluded from any vertical motion by the pins 612 and 612' which, however, allow part 638 to slide longitudinally along the two pairs of rails 613 provided in base plate 606. As noted previously, pin 612 also acts as the hinge joining parts 637 and 638.

The forward ends of both parts 637 and 638 are slotted, as shown at 651 and 652 respectively, to provide space for the retaining block 636 of the trigger mechanism (described hereinafter). To prevent parts 637 and 638 from sticking together under the effects of freezing temperature, separation is provided by means of two ridges 653 located at the forward end of part 638.

When the binding is released, carriage block 607 is propelled rearward under the action of tension springs 617 described previously. Once the boot is free of the binding, section 621 of retaining arms 608 no longer exerts pressure on these springs, and, therefore, the rearward motion of carriage block 607 ceases. The return of the carriage block 607 to the neutral position is accomplished by means of a weak spring 654 (FIG. 46) provided in a well 656 located on the underside of part 638. The rear part of the spring is attached to part 638 inside the well 656 and the forward part to a fixed block 657 that is permanently attached to the bottom of base plate 606, as shown in FIG. 45. Spring 654 is sufficiently weak not to oppose the decompression of springs 617 upon release of the binding, but yet strong enough to restore carriage block 607 to its neutral position once release is completed and the skier's boot is removed from the binding.

In FIG. 45 base plate 606 is shown with the carriage block 607 and retaining arm assembly 608 removed. Base plate 606 is fixed to the ski by means of six screws (not shown) inserted through holes 658 (one shown). The trigger mechanism of the binding provides for both COMMAND and AUTOMATIC releases. It consists principally of the retaining block 636, a limiting pin 659, a retaining block transmission arm 661, a trigger plate 662, and a trigger pin 663. Trigger pin 663 is connected directly to command release cable 32. When the binding is in the neutral or in the locked position, pin 663 is extended to the maximum into the binding itself so that trigger plate 662 which is attached thereto and can only move laterally, rests against the opposite wall of base plate 606. As the command release is actuated through a pull on command release cable 32, trigger pin 663 is drawn in the direction of the pull and trigger plate 662 follows thereby uncovering, through notch 664 the tip 666 of transmission arm 661. Retaining block 636 against which rests fin 632 (FIGS. 48 and 52) is now free to rotate rearward until arrested by limiting pin 659.

The position of limiting pin 659 is controlled by means of a bracket 667 held against the walls of base plate 606 by two side hinge pins 668. In the position shown, the binding is set for partial release. Pin 659 is lodged into two notches 669 of bracket 667 which prevent further motion rearward of pin 659. To set the binding at full release, bracket 667 is lowered to full down position inside the two slots 671 cut along the walls of base plate 606. The depression of bracket 667 to that position can be accomplished manually by pressing on tabs 672 (one shown) or by inserting a ski pole tip in the hole provided on tab 672 and pressing downward. Limiting pin 659 is positioned to either of the two alternative stations by translation along two slots 673 provided on the sides of base plate 606.

If pin 659 is in the forward position, depending on the setting selected for the binding, rotation will only be partial and fin 632 will come to rest against a partially depressed retaining block 636. In the resulting configuration, the binding will release the boot at lower thresholds of torsional or rotational forces than in its original setting. If, on the other hand, 70

limiting pin 659 is set to the extreme rear position, the rotation of retaining block 636 will be complete, clearing the passage of fin 632 and allowing full rearward motion of the carriage block 607 and retaining arm assembly 608. In this case the binding is fully released.

Once the skier's boot is removed from the binding retaining block 636 is forced to rotate forward to its original position by an extension spring 654 connecting the bottom of transmission arm 661 to base plate 606. Spring 654 also acts as a compensating force on retaining block 636 against the considerable pressure applied to fin 631 when the binding is loaded and locked. When the command release handles 200 are reset in the cocked position, release cable 32 returns to its neutral position forcing trigger plate 662, by means of trigger pin 663, back to its original position in which plate 662 overlaps the tip 666 of transmission arm 661, thereby locking the binding.

The only motion imparted to retaining block 636 is rotational about pin 676 to which it is rigidly attached. Also rigidly attached to retaining block 636 and hence also to pin 676 is transmission arm 661.

It is noted that the horizontal position of trigger plate 662 is assured at all times by means of two pairs of vertical tabs 677 extending from the plate itself downward against base plate 606.

As previously indicated, in the AUTOMATIC release mode either from the retaining block 636 position shown in FIG. 50 of after COMMAND release when retaining block 636 has rotated partially or fully, release results from the motion of fin 632 (FIG. 52) against the inner face of retaining block 636. This can result from an upward movement of the ski boot heel relative to the ski as shown by arrow 678, or by pivotal or sideways motion of the heel as shown by arrows 679, or by a combination of the two motions. Once fin 632 has cleared retaining block 636 the carriage block 607 and retaining arm assembly 608 are free to move rearward under the action of extension springs 617 (FIG. 43).

It is to be understood that the invention is not limited to the particular embodiments and features described and shown, but that it comprises any modifications and equivalents within the scope of the appended claims.

I claim:

1. Apparatus for securing a ski to a boot, which comprises: a toe unit for clamping the toe of the boot to the ski; a heel unit for clamping the heel of the boot to the ski; means for biasing at least one of said toe and heel units longitudinally away from the other to relax the grip on the boot therebetween; latch means for holding said toe and heel units in their gripping position during normal operating conditions; a command release means adapted to be held in the hand of the skier during the act of skiing for producing a release command when the hand of the skier opens; and means for transmitting the release command from said command means to said latch means to move said toe and heel units longitudinally apart so that the boot may be extricated from the ski.

2. Apparatus as recited in claim 1, wherein said toe unit moves forward upon the release of said latch means.

3. Apparatus as recited in claim 1, wherein said heel unit moves rearward upon the release of said latch means.

4. Apparatus for securing a ski to a boot, which comprises: a toe unit for clamping the toe of the boot to the ski; a heel unit for clamping the heel of the boot to the ski; means for biasing at least one of said toe and heel units longitudinally away from the other to relax the grip on the boot therebetween;

latch means for holding said toe and heel units in their gripping position during normal operating conditions; and means controlled by the skier during the acts of skiing for releasing said latch means on command to move said toe and heel units longitudinally apart so that the boot may be extricated from the ski, said releasing means comprising a command release mechanism adapted to be held in the hand of the skier; and

- a shielded cable connected at one end to said latch means and connected at the other end to said release mechanism for transmitting the release command from the skier to the latch means.
5. Apparatus as recited in claim 4, which further includes: a ski pole; and wherein said release mechanism is mounted on the handle end of said pole. 5
6. Apparatus as recited in claim 4, which further includes: a ski pole; and wherein said release mechanism includes; a handle grip connected to one end of the pole, one end of 10 said shielded cable being connected to the handle grip; and spring means for biasing said handle grip away from the pole upon release of the grip by the skier to pull the cable and thereby actuate the latch means on the command of the 15 skier.
7. Apparatus as recited in claim 6, which includes, means for holding the release mechanism in a safety position so that release of the handle grip does not result in a release of said latch means.
8. Apparatus as recited in claim 4, wherein said shielded cable is divided into at least three separable sections, a first of which is secured to the binding, a second of which is carried on the skier's body, and the third section is secured to the release switch, and which further includes, cable connectors for releasably connecting the first section to the second section, and the second section to the third section so that a skier may disengage himself from the binding and the release mechanism.
9. Apparatus as recited in claim 4, which comprises: 30 a separate shielded cable for each boot; a separate mechanism switch for each boot; and a release switch interconnecting the two release mechanisms, said release switch in one control setting having means for actuating both cables upon the actuation of either release mechanism and in another control setting for actuating the cables only when both release mechanisms are actuated.
10. In a ski binding of the cable release type, which includes a toe holding unit, a cable extending around the heel of the boot, and a spring biased lever mechanism for placing tension on the cable to urge the toe of the boot into the toe holding unit, the improvement which comprises: 40
- a command release means adapted to be held in the hand of the skier during the act of skiing for producing a release command when the hand of the skier opens; means responsive to the release command for releasing tension on the cable on command so that the boot can be extricated from the ski; means for transmitting the release command from said command means to the releasing means. 50
11. A ski binding as recited in claim 10, wherein said tension releasing means comprises:
- a release element mounted in the cable and adapted upon 55 actuation to lengthen the cable so as to relax the cable tension; a shielded cable connected at one end to said release element, said cable extending upwardly along the skier's torso to his hand; and
- a release mechanism adapted to be held in the hand of the skier and connected to the other end of the shielded cable for actuating the release element upon the command of the skier. 60
12. In a ski binding of the cable release type, which includes a toe holding unit, a cable extending around the heel of the boot, and a spring biased lever mechanism for placing tension on the cable to urge the toe of the boot into the toe holding unit, the improvement which comprises: 65
- means controlled by the skier during the act of skiing for releasing the tension on the cable on command so that the boot can be extricated from the ski, said tension releasing means comprising:
- means for normally urging said spring biased lever mechanism into an unloaded position; 70

- a latch for holding said spring biased lever mechanism in the loaded position parallel to the ski; a shielded cable connected at one end to said latch, said cable extending upwardly along the skier's torso to his hand; and a release mechanism adapted to be held in the hand of the skier and connected to the other end of the shielded cable for releasing the latch upon the command of the skier during the act of skiing.
13. In a ski binding of the cable release type, which includes a toe holding unit, a cable extending around the heel of the boot, and a spring biased lever mechanism for placing tension on the cable to urge the toe of the boot into the toe holding unit, the improvement which comprises:
- means controlled by the skier during the act of skiing for releasing the tension on the cable on command so that the boot can be extricated from the ski, and means for moving the toe binding unit forward as the tension in the cable is released.
14. Safety ski binding assembly for releasably securing a ski and boot together, comprising:
- binding means for releasably clamping a ski and boot together, 20
- latch means for holding said binding means in clamping position, 25
- a command release means adapted to be held in the hand of the skier during the act of skiing for producing a release command when the hand of the skier opens, and means for transmitting the release command from said command means to said latch means for releasing said latch means on command to release the boot from the ski.
15. A step-in ski binding in accordance with claim 14, for securing a boot to a ski, which comprises:
- an articulated sole plate having forward and rear segments hingedly connected at their juncture; means for hingedly connecting the rear edge of the rear segment to the ski; first spring means for normally urging said segments into an inverted V position with respect to said ski when no boot is in the binding, said spring means being placed in a loaded condition upon insertion of a boot into the binding; 45
- a heel binding and release unit mounted on said rear segment of the sole plate, said unit being moved into engagement with the heel of the boot as the boot, on insertion into the binding, urges the two segments of the sole plate into coplanar relationship, parallel to the ski;
- a transmission plate positioned under the sole plate and extending forwardly thereof, said transmission plate being movable in a longitudinal direction relative to the sole plate;
- a toe binding and release unit mounted on said transmission plate for fore and aft movement with said plate; second spring means biasing said transmission plate forwardly, said spring means being loaded as the sole plate is brought into parallel relationship with the ski; said latch means being associated with said transmission plate for normally holding said plate in its rearward position, thereby loading said second spring means, as the sole plate is brought into parallel relationship with the ski; and release of said latch means allowing the transmission plate and the toe binding and release unit to move forwardly so that the boot can be extricated from the ski.
16. A ski binding as recited in claim 15, which further comprises:
- means for releasably holding said toe binding and release unit on said transmission plate so that the unit moves forward relative to the plate upon a forward shock.
17. A ski binding as recited in claim 16, wherein said transmission plate is bifurcated and said toe binding and release unit is supported between the furcations, and wherein said holding means comprises:

spring biased latch means protruding from said toe binding release unit against an edge of the furcations, said latch means being disengaged from the furcations upon the exertion of a predetermined force against the toe binding and release unit.

18. A ski binding as recited in claim 17, which further comprises:

means for adjusting said spring biased latch means to release at different predetermined forces.

19. A ski binding as recited in claim 15, wherein said heel binding and release unit comprises:

means for releasing the boot from said when a predetermined lateral force is transmitted from the boot to the unit.

20. A ski binding as recited in claim 19, wherein said lateral releasing means comprises:

a hollow frame mounted on the rear segment of the sole plate, said frame having a generally horizontal camming surface;

a core member secured inside the hollow frame for rotation about a vertical axis, said member having a cam in engagement with said camming surface;

means for biasing said cam and cam surface together to restrain said core from rotating on its vertical axis under less than a predetermined force; and

a binding bracket mounted on said core and rotatable therewith, said bracket being disengaged from the boot when said core rotates on its vertical axis under more than said predetermined force.

21. A ski binding as recited in claim 20, wherein said core has a plurality of tiers, and said binding bracket is movable from one tier to another so that the bracket can be adjusted to the proper height with respect to the boot.

22. A ski binding as recited in claim 15, wherein said heel binding and release unit comprises:

means associated with said latch releasing means for releasing the boot from said unit when a predetermined upward force is transmitted from the boot to the unit.

23. A ski binding as recited in claim 22, wherein said upward releasing means comprises:

a depending hook movable upward with the heel binding and release unit for raising said latch releasing means to release the transmission plate.

24. A ski binding as recited in claim 15, wherein said means for transmitting the release command comprises:

a shielded cable connected at one end to said latch means and connected at the other end to said command release means for transmitting the release command from the skier to the latch means for releasing said latch means.

25. The apparatus of claim 14, which comprises:

a frame pivotally mounted about a transverse axis on the ski, said frame extending rearward therefrom;

a heel gripping and release unit mounted for fore and aft movement on said frame;

at least one transmission arm pivotally connected at one end to the heel gripping and release unit, and forming a triangular structure with the frame and the ski in the unloaded condition, the other end of said arm being mounted for movement longitudinally on the ski;

spring means associated with the frame and the heel gripping and release unit for normally biasing said unit rearward;

a latch mechanism for restraining the other end of the transmission arm against longitudinal movement during insertion of the boot into the binding, whereupon the frame and arm assume positions generally parallel to the ski, and the heel gripping and release unit moves forward and downward to engage the boot thereby placing said spring means in a loaded condition; and

means for releasing said latch means upon the application of predetermined forces to the heel gripping and release unit so that said frame and unit move rearward on the ski under the influence of said spring means whereby the boot can be extricated from the binding.

26. A stepin ski binding as recited in claim 25, which further comprises:

means for holding the frame in a position parallel to the ski once the boot has been inserted in the binding, said holding means being released by the rearward movement of the heel gripping and release unit upon release of said latch means.

27. In apparatus of claim 14, a stepin ski binding for securing the heel of a boot to a ski, said ski having a toe binding unit, the improvement which comprises:

a base plate secured to the ski rearwardly of the toe binding unit, said plate having openings on either side; a carriage block having projections extending therefrom into said openings for movement fore and aft on said plate;

a retaining arm connected to the forward part of said carriage block, said arm having means for clamping the heel of the boot and said arm being mounted for lateral pivotal movement with respect to said block;

means for restraining the pivotal movement of said arm about said block until a predetermined force is applied thereto at which time the arm moves laterally to permit release of the ski boot;

means for restraining the upward movement of said block and arm until a predetermined force is applied thereto at which time said block and arm move upwardly together to permit release of the ski boot; and

means for moving said carriage block and retaining arm rearwardly away from the boot when either of said predetermined forces are exceeded to facilitate separation of the boot and the ski.

28. A stepin ski binding as recited in claim 27, wherein said retaining block comprises:

a rear section connected to said carriage block and including a vertical pin on which the rear section pivots;

a forward section hingedly connected on a horizontal axis for vertical movement with respect to the rear section;

means for urging said forward section into a raised position at an acute angle to the rear section in preparation for loading with the boot, the longitudinal axes of said sections being colinear when the binding is loaded; and means for locking said sections in colinear relationship while the boot is secured in the binding.

29. Safety ski binding assembly for releasably securing a ski and boot together, comprising:

binding means for releasably clamping a ski and boot together;

latch means for holding said binding means in clamping position;

means controlled by the skier during the act of skiing for releasing said latch means on command to release the boot from the ski;

a command release mechanism adapted to be held in the hand of the skier; and

a shielded cable connected at one end to said latch means and connected at the other end to said release mechanism for transmitting the release command from the skier to the latch means.

30. Apparatus as recited in claim 29, which further includes:

a ski pole; and wherein said release mechanism is mounted on the handle end of said pole.

31. Apparatus as recited in claim 29, which further includes:

a ski pole; and wherein said release mechanism includes; a handle grip connected to one end of the pole, one end of said shielded cable being connected to the handle grip; and

spring means for biasing said handle grip away from the pole upon release of the grip by the skier to pull the cable and thereby actuate the latch means on the command of the skier.

32. Apparatus as recited in claim 31, which includes, means for holding the release mechanism in a safety position so that

23

release of the handle grip does not result in a release of said latch means.

33. Apparatus as recited in claim 29, wherein said shielded cable is divided into at least three separable sections, a first of which is secured to the binding, a second of which is carried on the skier's body, and the third section is secured to the release switch, and which further includes, cable connectors for releasably connecting the first section to the second section, and the second section to the third section so that a skier may disengage himself from the binding and the release mechanism. 5

24

34. Apparatus as recited in claim 29, which comprises: a separate shielded cable for each boot; a separate mechanism switch for each boot; and a release switch interconnecting the two release mechanisms, said release switch in one control setting having means for actuating both cables upon the actuation of either release mechanism and in another control setting for actuating the cables only when both release mechanisms are actuated.
